United States Patent Office.

RICHARD M. WILLIAMS, OF ROCKVILLE, MARYLAND.

Letters Patent No. 95,864, dated October 12, 1869.

HARVESTER.

The Schedule referred to in these Letters Patent and making part of the same

To all whom it may concern:

Be it known that I, RICHARD M. WILLIAMS, of Rockville, in the county of Montgomery, and State of Maryland, have invented a new and useful Improvement in Harvesters; and I do hereby declare that the following is a full, clear, and exact description of the construction and operation of the same, reference being had to the accompanying drawings, making part of this specification, in which—

Figure 1 is a rear elevation, and

Figure 2 is a plan view.

This invention consists,

First, in attaching the finger-bars and platforms to the frame-work of the machine, in such a manner that said finger-bars and platforms may rotate about a common centre in a horizontal plane.

Second, in a device for pulling cut grain upon the platforms, acting like a stationary reel.

Third, in a device for removing cut grain from the platforms in gavels.

In the drawings—

A' A' are the main driving-wheels, the axle A of which is supported at its ends in brackets a a, projecting downward from the under side of the circular frame B, the latter having a rim, b, which serves as a track for the friction-rollers c' to run on, which rollers support the wheel C, running on a spindle at the centre of the circular frame B.

The wheel C has cogs on the lower part of its rim, by means of which it is connected, through suitable gearing, with the fixed spur-gear of the main driving-wheels.

Upon the same spindle that forms the axis of the wheel C are loosely placed the bands or rings, at the inner ends of the bracket-supports c of the finger-bars, the hub running up far enough on the spindle to admit them, the bracket-supports being connected with the spokes of the wheel C, and resting on them, by wooden pins, which break easily enough to admit of the severance of such connection, against the stress of an obstruction met with by the platforms attached to the lower and outer ends of the bracket-supports c, and too powerful to be removed thereby, thus preventing fracture of more important parts of the machine.

The attachment of the platforms D to the lower and outer ends of the bracket-supports c is effected by slotted bars d, on the latter, and set-screws.

On the common spindle, above the extensions, is a rigid circular frame, E, the periphery of which is toothed, with which teeth engage the cogs of the vertical shaft e e, revolving in boxes in the bracket-supports c, which vertical shafts rotate the crank-wheels c', the latter communicating their reciprocating motion to the sickle-bars.

As the machine advances, the opposite platforms D revolve in a horizontal plane, cutting a swath about equal in width to the distance from the centre of the frame to the outer end of either finger-bar. This arrangement also quite avoids side-draught.

The wheels C and circular frame E should be of sufficient diameter to afford all necessary leverage to the rotation of the platforms.

The finger-bars and platforms, not being required to support any of the weight of the machine, may be made very light.

To the top of the circular frame E is affixed the rear end of the wooden frame-work F, that supports the driver's seat at its front end, and is itself sustained there upon a vibrating axle, F', and wheels F'' F'', of a diameter small enough to run under the frame-work F, so as to turn as short as wanted.

To one side (right or left, as the operator may prefer,) of the rear of the frame F, projects a beam, G, that sustains a horizontal shaft, G', having an arm, h, projecting from it, that hooks at its outer end into a loop, h', in the centre of the cross-bar h'', which joins the tops of a pair of vertical rods, i i, that pass down through the beam G, through tubes l l, affixed to the under side of said beam, and having a rake-head, k, fastened to their lower ends, the teeth of which project down nearly or quite to the level of the platforms.

The function of the rake is to sweep the cut grain from the platforms D as they come round under it.

A foot-lever, k', under the driver's seat, is so connected with the shaft G', that by a gentle pressure of the foot, the rake may be raised, and the platform be thus allowed to take two or more revolutions before being cleared of its load, and the driver regulate the size of the gavels at his option, according to the lightness or heaviness of the grain.

From the frame F, always in the opposite direction to the rake, projects a beam, H, carrying a series of horizontal fingers, l', which move through the grain, condensing it for the operation of the sickle-bar, when it shall come round, the length of the fingers being so varied as that those above the sickle-bar shall always project over the outermost teeth of the latter.

After the grain is cut, the fingers l' uphold it till it settles down on the platform, immediately in the wake of the cutters,

Having thus described my invention,

What I claim as new, and desire to secure by Letters Patent, is—

1. The platforms D and finger-bars, placed opposite each other, and arranged so as to rotate, with their sickle-bars, in a horizontal plane, about a com-

thor centre, substantially as and for the purposes explained.

2. In combination with the revolving platforms and the finger-bars, the beam H, carrying the graded series of fingers l, arranged to operate in the manner and to the end set forth.

3. In combination with the revolving platforms and finger-bars, the beam G, carrying the adjustable

rake k, arranged to act as described, and with the extent specified.

RICHD. M. WILLIAMS.
